UNITED STATES PATENT OFFICE.

PAUL T. KENNY, OF NEW YORK, N. Y., ASSIGNOR TO ELEVATOR SUPPLY & REPAIR COMPANY, A CORPORATION OF ILLINOIS.

ELEVATOR SIGNALING APPARATUS.

1,173,192.

Specification of Letters Patent.

Patented Feb. 29, 1916.

Application filed October 3, 1907. Serial No. 395,696.

To all whom it may concern:

Be it known that I, PAUL T. KENNY, a citizen of the United States, residing in the borough of Manhattan, in the county, city, 5 and State of New York, have invented certain new and useful Improvements in Elevator Signaling Apparatus, of which the following is a specification, such as will enable others skilled in the art to which it applies 10 pertains to make and use the same.

My invention relates to an elevator signaling apparatus, and my object is to improve and simplify the construction.

One of my objects is to provide a series of 15 electrically-operated visual signals, one for each floor, for each car, with mechanism for operating the same in each direction of movement of the car by means of up and down controllers at each floor to be operated 20 by the passengers, and which I have generically termed "passenger's buttons".

Another object is to provide a particular arrangement of mechanism for restoring to normal condition the mechanism set by the 25 passenger's buttons.

A further object is to provide a construction by which the elevator gates or doors at the floors may restore to normal condition the mechanisms set by the passenger's buttons 30 and which shall be more economical in wiring than has heretofore been the case in prior devices.

My invention will be set forth in the 35 claims.

In the preferred embodiment of my invention shown in the drawings, Figure 1 represents a general diagrammatic view; Fig. 2 a detail of the same; and Fig. 3 a diagram still more simplified than Fig. 1. Fig. 4 is a 40 further diagram of a portion of a construction shown in Fig. 1.

All these drawings are diagrammatic and are intended to show the main features of the apparatus more clearly than constructional drawings will do.

I have shown my invention diagrammatically in the drawings instead of by illustrating the same in its particular mechanical construction, because it may be more readily understood and appreciated and it will

be evident to any mechanic skilled in the art how my invention could be embodied, and I believe that a more thorough understanding of the invention may be had from the diagram than by illustrations of the particular 55 mechanical devices which might be made use of.

Referring to the drawings, 1 and 2 represent elevator cars moved up and down in their shafts by a suitable hoisting mechanism not shown, and passing the floor gates or doors 3, 4, 5 and 6. The gates 3 and 5 are assumed to be at the third floor, and 4 and 6 at the fourth floor, for example. I have shown in each car a series of electrically-operated visual signals, such as ordinary incandescent lamps 7 and 8 in car 1, and 9 and 10 in car 2, the lights 7 and 9 representing the third floor, and 8 and 10 the fourth floor. In order to operate the same I have 70 provided at each floor up and down mechanism to be operated by the intending passengers and which I have generically termed "passenger's buttons". 11 and 12 represent the up and down passenger's buttons at 75 the third floor, and 13 and 14 those at the fourth floor. They may obviously be of any desired construction, as will be evident to any one skilled in the art.

I have provided mechanism corresponding to each button which is set by its button when the latter is operated, preferably by closing a break in a normally-open circuit. In the construction illustrated in the drawings I have provided setting magnets 15, 80 16, 17 and 18, connected to the passenger's buttons 11 to 14, respectively, at one side, and at the other side connected to contacts 19, 20, 21 and 22. 23 to 26 represent pivoted switch arms which normally rest upon their 85 respective contacts just named, as indicated by 23, 26, for example, and said levers may be connected to the return wire 27, which leads back to the source of electro-motive source as indicated, for example, by dynamo 90 28. When the button 12, for example, is pressed, a circuit will be closed from the dynamo through the button magnet 16, contact 20, switch arm 23, and back to the dynamo, thus energizing the setting mag- 100

net 16 and drawing the switch arm over to the position of switch arm 25, that is, so that the switch arm 23 will leave contact 20 and touch a contact 29. Each of the other switch arms is provided with a contact similar to 29, as indicated by 30 to 32. The switch arms 24 and 25 are represented in full lines as having been thrown, the up button 11 on the third floor, and the down button 14 on the fourth floor, being assumed to have already been operated. When a switch arm is thrown to its set position, it would immediately light up one of the lights in the car, providing that the circuit from that light was closed by the switch arm as soon as it was thrown, but instead of lighting up the light immediately I have preferred to provide a commutator which co-operates with the mechanism which is set by the push-button so that neither one alone will display the signal. In the embodiment shown in the drawings the commutator for car 1 comprises fixed contacts 33 to 36 and a moving contact 37 which is moved correspondingly with the movement of the car, although usually much slower as is common in the art. The commutator for car 2 comprises similar fixed and moving contacts represented by 38 to 42.

In order that only the proper signals may be given, that is, in order that an up signal shall not be given for a car which is moving downwardly, and vice versa, I have provided what I have termed a directional means which is operated by the movement of the car as it reverses its direction of movement, so as to render the mechanisms which have been set by the up passenger's buttons, for example, incapable of co-operating with the commutator to display the signals when the car is moving down, and vice versa, so that false signals will not be given. In the construction indicated in Fig. 1 I have provided a vibrating switch for each car indicated generically by 44 and 45, which are thrown when the cars reverse their direction of movement, as will be evident to any one skilled in the art. The car 1 at the left is indicated as moving downwardly, and the switch 44 is indicated in its down position. Car 2 is indicated as moving upwardly, and switch 45 is shown in its up position. A wire 46 from contact 36 leads to the movable contact 47, and from contact 34 a wire 48 leads to contact 49. 50 and 51 represent stationary contact springs which, when the switch is in the position shown, contact with 47 and 49 so as to close the breaks. Referring to car 1, it will be seen that a circuit has been closed through lamp 8 which is indicated as lighted. The circuit may be traced from lamp 8, through the commutator contacts 35, 37, 36, by wire 46 to contact 47, to contact 50, through magnet 84 to contact 31, switch lever 25 and back to the source of supply. It will be observed that even with the switch 44 in the position indicated, the signal 8 is operable only by the joint action of the commutator and a passenger's-button-set mechanism corresponding to the signal, that is, neither one alone can operate the signal. I prefer to so arrange the moving and stationary parts of the commutator that the signal will be displayed only when the car is approaching the floor corresponding to that signal, and is, for example, one or two floors away.

53 and 54 are stationary contact springs similar to 50 and 51 which engage with the portions 49 and 47 when the switch is thrown over to the left. The directional switch 45 is provided with four similar stationary contact springs 55 to 58. The car 2 is moving up and the switch 45 has been thrown so that the bridging contacts 59 and 60 are touching the springs 55 and 56. From the stationary contacts 38 and 40 wires 62 and 61 are connected to the bridging contacts 59 and 60, respectively, which latter contacts therefore close the circuit from the stationary contacts to the springs 55 and 56. As the springs 55 and 53 are both connected with the up passenger's-button-set lever 24 of the third floor, and the car 2 is adjacent to and moving toward the third floor, a circuit will be closed from contact 38 of the commutator by wire 62 and spring 55 to the stationary contact 30 of the up mechanism for the third floor, and from there by passenger's-button-set switch-arm 24 and return wire to the source of supply. This will light up the lamp 9 in car 2 and signal the car to stop at the third floor. If the up push-button 13 were also pushed the light 10 would also light up, because as shown at 42 the moving contact of the commutator is arranged to touch the stationary contacts at times such that the signal will be given about two floors ahead of where the car is to stop. It will also be obvious that when the directional switch 45 is thrown to the opposite position, it will touch the contacts 57 and 58 to put the commutator for car 2 in communication with the "down" passenger's-button-set levers for both floors, and that when the directional switch 44 is thrown to the left it will touch contacts 54 and 53 and put the commutator of car 1 in communication with the "up" passenger's-button-set levers. In order to throw these switches as the cars reverse their direction of movement, various means may be employed as will be evident to any one skilled in the elevator art, but a convenient mechanism is a loose or frictional connection with the overhead mechanism (not shown) which will throw a contact in one direction or the other. I have indicated

such a construction for car 2 at 63, comprising a part frictionally driven in any suitable way from the overhead mechanism and which carries a contact 64 which, when the 5 car is moving upwardly, will touch a spring contact 65, and when the car is moving downwardly will be thrown over to touch a contact 66. 67 and 68 are magnets connected to the stationary spring contacts 69 10 and 70, respectively, which are alternately engaged by the common contact 71. When the switch 45 is in the position shown and the car reverses its direction of movement, the contact 64 will touch the spring 66, energize magnet 68 (because a circuit is closed 15 through the magnet and by wire 72 to return wire 27) and throw the switch over to the right to the down position of the switch, that is, to the same position as indicated by 20 switch 44. This will break the circuit through magnet 68 as contacts 70 and 71 will separate. Contact 71 will, when the switch is thrown, engage with the contact 69 ready to throw the switch 45 back to its 25 present position when the car again moves upwardly. It will be observed that switch 45 constitutes one form of a directional means operated by the movement of the car and rendering the up passenger's-button-set 30 mechanisms incapable of coöperating with the commutator of that car to display the signal when the car is moving down, and vice versa, that is, when car 2 is moving down, for example, the mechanism set by the 35 up push-buttons cannot coöperate with the commutator of car 2 to give the signals, and vice versa.

The car 1 has a similar arrangement for throwing the directional switch 44, 73 being the frictionally-driven portion, with its 40 contact 74, stationary contacts 75 and 76, magnets 77 and 78, spring contacts 79 and 80 and common contact 81.

In order to restore the passenger's-button-set mechanisms to normal condition, various 45 means may be provided, but I prefer to accomplish the restoration by mechanism operated by the floor gates or doors. Various mechanisms have been proposed in the prior 50 art for restoring push-button-set mechanism to normal condition by means of the operation of the floor gates, but I have been enabled to accomplish this with a saving in wiring which is advantageous in many instances. In the construction shown I have 55 provided a normally-open restoring circuit for each floor, and these circuits are preferably independent of each other so that the closure of one such circuit cannot restore 60 the passenger's-button-set mechanism of any other floor. These circuits control the restoration of the mechanisms which have been set, to normal condition, preferably by actually causing such restoration

by means of mechanism operated by the 65 said circuits.

Referring to the embodiment of my invention illustrated in Fig. 1, 83 to 86 are restoring magnets which when fully energized operate to draw the switch arms 23 to 70 26 to the left to break the signal circuits and restore the switch arms to normal condition. It will be observed that these magnets are shown to be in series with the lights in the cars. Each of these incandescent lamps obviously comprises an ohmic resistance, and the magnets may be so wound that when the circuit through the corresponding light and a magnet is closed, enough current will pass to light up the 80 light, but not enough to fully energize the magnet. If the light is short-circuited, however, by a shunt around the same, enough current will flow to the magnet to fully energize the same, that is, sufficiently 85 to restore the push-button-set mechanism to normal condition. I have provided such a shunt or short circuit around each light for this purpose. Referring to Fig. 2 which shows a detail of the up circuit for lamp 9, 90 it will be observed that current is passing through the restoring magnet 85, but not sufficiently to fully energize the same. 87, 88 is one of the restoring circuits which, it will be observed, comprises a short circuit 95 around the lamp. When the switch 89 (which represents the door switch) is closed, sufficient current will pass to the magnet 85 to fully energize the same and draw the switch arm 24 to its normal position, where it will make contact with contact 19, or, in other words, to restore the push-button-set mechanism to normal condition, in this case also restoring the signal 100 to normal condition.

Referring to Fig. 1, the restoring circuit just described is indicated by the same figures of reference. 90 and 91 are stationary terminals closed by contact 89 mounted on a pivoted arm 92 under constant stress from 110 spring 93. So long as gate 5 is closed it holds the arm 92 in the position shown, so that the restoring circuit is open, but when the gate is opened in the direction of the small arrow, the portion 89 will close the break 115 between the terminals 90 and 91, thus short-circuiting lamp 9, as current will pass by wire 88 to wire 62 and back to magnet 85, as before described. Each of the other floor gates is provided with a similar switch indicated by 94 to 96, and as each of the other signals is provided with a similar short circuit closed by such switches, it will be observed that the same operation takes place for the particular push-button-set mechanism controlled by the switch. It will also be observed that the directional switches 120 prevent the restoration to normal condition

of any push-button-set mechanism, except those corresponding to the direction of movement of the cars, that is, with the switch 45 in the position shown the opening 5 of gate 6 would not restore the down switch arm 25, nor would gate 5 restore the down switch 23 if push-button 12 had been operated. The switch 45 therefore is one form 10 of mechanism automatically connecting the restoring circuits with only those magnets corresponding to the up passenger's-button-set mechanisms when the car 2 is moving up, and vice versa. Obviously the directional switch 44 has the same function with relation to the circuits corresponding to car 1. 15

The provision of a single restoring circuit for each floor gate and directional switch mechanism throwing the circuits into connection with the up or with the 20 down magnets which control the restoration, is of advantage, because it does away with the necessity of running more than one circuit to each floor gate, and if these restoring circuits are independent of each 25 other as they are shown to be in the diagram, the opening of one gate will not restore to normal condition the push-button-set mechanism of any other floor. In Fig. 3 I have shown in simplified diagram the construction illustrated in Fig. 1, so that it may 30 be more easily followed, similar portions being indicated by the same reference characters. I have shown this figure to more clearly indicate the prominent features of 35 the diagram shown in Fig. 1.

In Fig. 4 I have shown a diagram of Fig. 1 indicating how the up-and-down restoring switches are connected with the restoring magnets through the directional 40 switches which are thrown by the car's movement, and that it is only necessary to have one wire from each switch in its own shaft.

I am aware that my invention may be embodied in constructions widely different in 45 appearance from those illustrated in the drawings, and I therefore do not confine myself to the construction shown.

What I claim is:

50 1. In an elevator signaling apparatus in combination, a car, a series of electrically-operated signals, one for each floor, carried by the car, means for operating the same comprising an up and down passenger's button at each floor, mechanism corresponding 55 to each button set by its button, and a commutator, connections whereby said signals are operable only by the joint action of said commutator and a passenger's-button-set mechanism corresponding to the signal, said commutator comprising a part moved correspondingly with the car and adapted to cooperate with said button-set-mechanisms in succession in each direction 60 of its movement to operate said signals, 65

and directional means operated by the movement of the car and rendering the "up" passenger's-button-set mechanisms incapable of coöperating with the commutator to operate the signals when the car is moving down, and vice versa. 70

2. In an elevator signaling apparatus in combination, a car, a series of electrically-operated signals, one for each floor, carried by the car, means for operating the same 75 comprising an up and a down passenger's button at each floor, mechanism corresponding to each button set by its button, and a commutator, connections whereby said signals are operable only by the joint action of said commutator and a passenger's-button-set mechanism corresponding to the signal, said commutator comprising a part moved correspondingly with the car and adapted to coöperate with said button-set-mechanisms in succession in each direction of its movement to operate said signals, directional means operated by the movement of the car and rendering the "up" passenger's-button-set mechanisms incapable of coöperating 80 with the commutator to operate the signals when the car is moving down, and vice versa, and restoring mechanism to automatically restore said passenger's-button-set mechanisms to normal condition. 90

3. In an elevator signaling apparatus in combination, a plurality of cars, a series of electrically-operated signals, one for each floor, carried by each car, means for operating the same comprising an up and a down passenger's-button at each floor, mechanism corresponding to each button set by its button, and a commutator for each elevator, connections whereby said signals are operable only by the joint action of a commutator and a passenger's-button-set mechanism corresponding to the signal, each of said commutators comprising a part moved correspondingly with its car and adapted to coöperate with said button-set-mechanisms 100 in succession in each direction of its movement to operate said signals, and directional means for each car operated by the movement of its car and rendering the "up" passenger's-button-set mechanisms incapable of coöperating 105 with the commutators to operate the signals when the cars are moving down, and vice versa. 110

4. In an elevator signaling apparatus in combination, a plurality of cars, a series of electrically-operated signals, one for each floor, carried by each car, means for operating the same comprising an up and a down passenger's button at each floor, mechanism corresponding to each button set by its button, and a commutator for each elevator, connections whereby said signals are operable only by the joint action of a commutator and a passenger's-button-set mechanism corresponding to the signal, each of 115 120 125 130

- 5 said commutators comprising a part moved correspondingly with its car and adapted to coöperate with said button-set-mechanisms in succession in each direction of its movement to operate said signals, directional means for each car operated by the movement of its car and rendering the "up" passenger's-button-set mechanisms incapable of coöperating with the commutators to operate the signals when the cars are moving down, and vice versa, and restoring mechanism to automatically restore said passenger's button-set mechanisms to normal condition.
- 10 5. In an elevator signaling apparatus in combination, an electric signal comprising an ohmic resistance, means for setting the signal comprising a passenger's button at a floor and mechanism set by said passenger's button, restoring mechanism for restoring said passenger's-button-set mechanism to normal condition and comprising a magnet in series with said signal, mechanism operated by said magnet when fully energized to 20 restore the button-set mechanism to normal condition, a normally-open shunt circuit around said resistance, and means for closing said shunt circuit to fully energize said magnet.
- 25 6. In an elevator signaling apparatus in combination, an electric signal comprising an ohmic resistance, means for setting the signal comprising a passenger's button at a floor and mechanism set by said passenger's button, restoring mechanism for restoring said passenger's-button-set mechanism to normal condition and comprising a magnet in series with said signal, mechanism operated by said magnet when fully energized to 30 restore the button-set mechanism to normal condition, a normally-open shunt circuit around said resistance, and means for closing said shunt circuit to fully energize said magnet.
- 35 7. In an elevator signaling apparatus in combination, a car, electrically-operated signaling means, mechanism for operating the same comprising an up and a down passenger's button at each floor and mechanism for each button set by operation of the corresponding button, a gate at each floor, restoring mechanism adapted to restore said passenger's-button-set mechanisms to normal condition and comprising a normally-open 40 restoring switch for each floor closed by operation of its corresponding gate and a magnet corresponding to each passenger's-button-set mechanism and adapted to control the restoration of the same, and mechanism automatically connecting said restoring switches with only those magnets corresponding to the up passenger's-button-set mechanisms when the car is moving up, and vice versa, and a commutator having a part moved correspondingly to the movement of the car and arranged to cause the operation of a signal only when said car is approaching the floor to which said signal corresponds.
- 45 8. In an elevator signaling apparatus in combination, a car, electrically-operated signaling means, mechanism for operating the same comprising an up and a down passenger's button at each floor and mechanism for each button set by operation of the corresponding button, a gate at each floor, restoring mechanism adapted to restore said passenger's-button-set mechanisms to normal condition and comprising a normally-open restoring switch for each floor closed by operation of its corresponding gate and a magnet corresponding to each passenger's-button-set mechanism and adapted to control the restoration of the same, and mechanism automatically connecting said restoring switches with only those magnets corresponding to the up passenger's-button-set mechanisms when the car is moving up, and vice versa, said restoring switches being independent of each other whereby the closure of one of said switches cannot restore the passenger's-button-set mechanism of any other floor, and a commutator having a part moved correspondingly to the movement of the car and arranged to cause the operation of a signal only when said car is approaching the floor to which said signal corresponds.
- 50 9. In an elevator signaling apparatus in combination, a car, electrically-operated signaling means, mechanism for operating the same comprising an up and a down passenger's button at each floor and mechanism for each button set by operation of the corresponding button, a gate at each floor, restoring mechanism adapted to restore said passenger's-button-set mechanisms to normal condition and comprising a normally-open restoring switch for each floor closed by operation of its corresponding gate and a magnet corresponding to each passenger's-button-set mechanism and adapted to restore the same to normal condition, and mechanism automatically connecting said restoring switches with only those magnets corresponding to the up passenger's-button-set mechanisms when the car is moving up, and vice versa, and a commutator having a part moved correspondingly to the movement of the car and arranged to cause the operation of a signal only when said car is approaching the floor to which said signal corresponds.
- 55 10. In an elevator signaling apparatus in combination, a car, a signaling device for each of a plurality of floors, means for operating the same comprising an "up" and a "down" passenger's-button for each floor and mechanism for and set by each button and a part moved correspondingly with the

car and adapted to coöperate with said mechanisms to operate all said signaling devices in succession in each direction of movement of the car, said means also including 5 mechanism rendering said moving part incapable of so coöoperating with the "up" passenger's-button-set mechanisms when the car is moving down, and vice versa.

11. In an elevator signaling apparatus in 10 combination, a car, a signaling device for each of a plurality of floors, means for operating the same comprising an "up" and a "down" passenger's-button for each floor and mechanism for and set by each button 15 and a part moved correspondingly with the car and adapted to coöperate with said mechanisms to operate all said signaling devices in succession in each direction of movement of the car, said means also including 20 mechanism rendering said moving part incapable of so coöoperating with the "up" passenger's-button-set mechanisms when the car is moving down, and vice versa, another car, and means corresponding individually 25 thereto for restoring the said passenger's-button-set mechanisms to normal condition.

12. In an elevator signaling apparatus in combination, a car, a signal-controlling circuit for each of a plurality of floors, a signaling device for each floor, each operated by one of said circuits, means controlling said circuits and comprising an "up" and a "down" passenger's-button for each floor and mechanism for and set by each button 30 and a commutator coöperating therewith and having a part moved correspondingly with the car and adapted to close all said signal circuits in succession in each direction of movement of the car, said means also 35 including mechanism rendering said moving part incapable of so coöoperating with the "up" passenger's-button-set mechanisms when the car is moving down, and vice versa.

13. In an elevator signaling apparatus in 45 combination, a car, a signal-controlling circuit for each of a plurality of floors, a signaling device for each floor, each operated by one of said circuits, means controlling said circuits and comprising an "up" and a "down" passenger's-button for each floor and mechanism for and set by each button 50 and a commutator coöperating therewith and having a part moved correspondingly with the car and adapted to close all said 55 circuits in succession in each direction of movement of the car, said means also including mechanism rendering said moving part incapable of so coöoperating with the "up" passenger's-button-set mechanisms 60 when the car is moving down, and vice versa, another car, and means corresponding individually thereto for restoring said passenger's-button-set mechanisms to normal condition.

65 14. In an elevator signaling apparatus in

combination, a car, a signal-controlling circuit for each of a plurality of floors, a signal lamp for each floor each operated by one of said circuits, means controlling said circuits and comprising an "up" and a "down" passenger's-button for each floor and mechanism for and set by each button and a commutator coöperating therewith and having a part moved correspondingly with the car and adapted to close all said signal circuits in 70 succession in each direction of movement of the car, said means also including mechanism rendering said moving part incapable of so coöoperating with the "up" passenger's-button-set mechanisms when the car is moving down, and vice versa.

15. In an elevator signaling apparatus in combination, two cars, and for each floor and corresponding to each car a single signaling device adapted to cause a signal to be 75 given in each direction of movement of its car, means for operating the same in each direction of movement of the cars and comprising an "up" and a "down" passenger's-button at each floor, and for each button signal-controlling mechanism set whenever that button is operated and adapted to control the operation of the corresponding signaling devices for that floor, and for each car switch mechanism automatically operated by 80 that car and rendering the "up" passenger's-button set mechanisms incapable of controlling the operation of the said signaling devices corresponding to that car while that car is moving down, and restoring 85 mechanism corresponding to each car for restoring the passenger's-button-set mechanisms.

16. In an elevator signaling apparatus in combination, two cars, and for each floor and corresponding to each car a single lamp adapted to cause a signal to be given in each direction of movement of its car, means for operating the same in each direction of movement of the cars and comprising an "up" and a "down" passenger's-button at each floor, and for each button signal-controlling mechanism set whenever that button is operated and adapted to control the operation of the corresponding lamps for 110 that floor, and for each car switch mechanism automatically operated by that car and rendering the "up" passenger's-button-set mechanisms incapable of controlling the operation of the said lamps corresponding to that car while that car is moving down, and restoring mechanism corresponding to each car for restoring the passenger's-button-set mechanisms.

17. In an elevator signaling apparatus in combination, two cars, and for each floor and corresponding to each car a single signaling device adapted to cause a signal to be given in each direction of movement of its car, means for operating the same in each direc- 115 120 125 130

tion of movement of the cars and comprising an "up" and a "down" passenger's-button at each floor, and for each button signal-controlling mechanism set whenever that button is operated and adapted to control the operation of the corresponding signaling devices for that floor, and for each car switch mechanism automatically operated by that car and rendering the "up" passenger's-button-set mechanisms incapable of controlling the operation of the said signaling devices corresponding to that car while that car is moving down, and a commutator operated by that car and causing its signals to be given successively, and restoring mechanism corresponding to each car for restoring the passenger's-button-set mechanisms.

18. In an elevator signaling apparatus in combination, two cars, and for each floor and corresponding to each car a single signaling device adapted to cause a signal to be given in each direction of movement of its car, means for operating the same in each direction of movement of the cars and comprising an "up" and a "down" passenger's-button at each floor, and for each button a single signal-controlling mechanism set whenever that button is operated and adapted to control the operation of the corresponding signaling devices for that floor, and for each car switch mechanism automatically operated by that car and rendering the "up" passenger's-button-set mechanisms incapable of controlling the operation of the said signaling devices corresponding to that car while that car is moving down, and restoring mechanism corresponding to each car for restoring the passenger's-button-set mechanisms.

19. In an elevator signaling apparatus in combination, a car, a signal, means for operating the same comprising a passenger's-button on a floor and a device set thereby whenever said passenger's-button is operated, a magnet arranged to control the restoration of said device, a circuit therethrough having a normally-open switch automatically closed when said passenger's-button is operated and said device is set, a short circuit arranged to control the restoration-operation of said magnet, and a circuit-shifting switch operated by the car and automatically rendering said short circuit incapable of controlling the magnet during one direction of movement of the car.

20. In an elevator signaling apparatus in combination, a car, signaling means, means for operating the same comprising up and down mechanisms corresponding to a floor and arranged to be set by a passenger on a floor, a restoring magnet for each passenger-set mechanism and a circuit therefor having a normally-open switch therein closed automatically when said passenger-set mechanism is moved to its signal-set-

ting position, a single normally-open switch controllable by the car operator, and circuit-shifting mechanism serving to connect said single normally-open switch with said restoring magnets alternately.

21. In an elevator signaling apparatus in combination, a car, signaling means, means for operating the same comprising up and down setting circuits and mechanism corresponding to and set by each circuit, and means operated by the passenger on the floor for closing said circuits, an electrically-controlled restoring means for each passenger-set mechanism, a single normally-open switch controllable by the car operator, and a circuit-shifting switch serving to connect said single normally-open switch with said restoring means alternately, said circuit-shifting switch being independent of said setting circuit whereby the passenger may close a setting circuit at any time and irrespective of the direction said car or any other car may be moving.

22. In an elevator signaling apparatus in combination, a car, a single signaling means for each of a plurality of floors, means for operating the same in each direction of movement of the car comprising a commutator adapted to operate each signal as the car approaches its floor and up and down signal-controlling mechanism corresponding to each direction of movement of the car and arranged to be set by a passenger on a floor, another car having a similar signaling device for each floor controlled by said passenger-set mechanisms, and circuit-shifting mechanism arranged to prevent the down passenger-set mechanism from transmitting a signal to an up-moving car when the other car is moving down.

23. In an elevator signaling apparatus in combination, a car, signaling means, means for operating the same comprising an up and a down passenger's-button at a floor and mechanism corresponding to and set by each button, an electrically-controlled restoring magnet and circuit for each passenger's-button-set mechanism, circuit changing mechanism including a single normally-open switch and a circuit-shifting switch serving to connect said single normally-open switch with said restoring magnets alternately, said circuit-changing mechanism also including a part moved correspondingly with the car during its travel and adapted to coöperate with said circuit-shifting switch inclosing the circuits to said magnets, whereby the circuits through said normally open switch and to said magnets are closed only when the car is near the said floor.

24. In an elevator signaling apparatus in combination, a car, an electrically-operated signal-giving device and circuit therefor, a commutator adapted to close said circuit as

the car approaches a floor in each direction of movement, an up and a down setting circuit, passengers' buttons and switches operated thereby for closing said circuits, a 5 circuit-shifting switch adapted to connect said first circuit with said setting circuits alternately, and means for restoring the setting-circuit switches.

Signed at the borough of Manhattan in the county, city and State of New York, this 28 day of September A. D. 1907.

PAUL T. KENNY.
